(57) **CLAIM**

The ornamental design for a suture loop anchor, as shown and described.

DESCRIPTION

FIG. 1 is a perspective view of a suture loop anchor showing a first embodiment our new design;

FIG. 2 is a front elevational view of the suture loop anchor of FIG. 1;

FIG. 3 is a rear elevational view of the suture loop anchor of FIG. 1;

FIG. 4 is a side elevational view of the suture loop anchor of FIG. 1;

FIG. 5 is a top view of the suture loop anchor of FIG. 1;

FIG. 6 is a bottom view of the suture loop anchor of FIG. 1;

FIG. 7 is a perspective view of a suture loop anchor showing a second embodiment our new design;

FIG. 8 is a front elevational view of the suture loop anchor of FIG. 7;

FIG. 9 is a rear elevational view of the suture loop anchor of FIG. 7;

FIG. 10 is a side elevational view of the suture loop anchor of FIG. 7; and,

FIG. 11 is a top view of the suture loop anchor of FIG. 7; the bottom view being a mirror image thereof.
